PRIMER TUBE FOR DYNAMITE CARTRIDGES

George R. Mustaparta, Kingston, N. Y., assignor to Hercules Powder Company, Wilmington, Del., a corporation of Delaware

Application March 25, 1941, Serial No. 385,087

6 Claims. (Cl. 102—22)

This invention relates to explosive primer devices and more particularly to an improved explosive primer tube containing a firing device and of such size as to receive an explosive cartridge.

According to well known practice explosive charges are fired by the use of firing devices such as blasting caps inserted in or attached to one of the cartridges of the explosive that makes up the charge. The combination of a firing device such as a fuse or electric blasting cap with an explosive cartridge is known in the art as a primer.

There are many ways of making a primer. Thus according to one method the cap is inserted into a hole made in the end of the cartridge and the cartridge paper folded around the cap and tied. According to another method the cap is inserted through the side of the cartridge and the fuse tied to or looped around the cartridge. Other modifications of the above methods are possible. However, in all of them the firing device is attached to or inserted in the completed dynamite cartridge in some manner.

In many operations, the primers described above are made up at a point remote from the shooting face to provide an added degree of safety and to effect a saving in loading and firing time. In other operations, due to company rules, local law, etc., it is necessary to take the explosive cartridges and caps to the shooting face separately and there prepare the primers. This type of operation is time consuming and adds a considerable element of danger, particularly under conditions where the operator is working in semi-darkness. Even when the primers are prepared beforehand the prior art methods are subject to the disadvantage of being tedious and time consuming.

In order to overcome these difficulties it has been suggested that a complete unit comprising a tubular member of cardboard, paper or other suitable material be made up and that the firing device be made an integral part of this unit. Such a device has been called a primer tube, and is described and claimed in the pending application of Lawrence W. Early, Serial No. 299,161, filed October 12, 1939, now Patent No. 2,301,384. Thus, when it is desired to make the primer it is only necessary to insert the explosive cartridge into the tubular member or primer tube. This can be done very easily and expeditiously by the operator even under conditions of semi-darkness.

The present invention relates to improvements in primer tubes whereby the insertion of an explosive cartridge is rendered easier and less likely to loosen or dislodge the firing device.

It is, therefore, an object of the present in-

vention to construct a primer tube device which permits the easy and quick assembly of a complete primer, even under very adverse conditions.

It is a further object of the invention to provide a primer tube, having a blasting cap securely fastened thereto in such manner that an explosive cartridge may be quickly and easily inserted into the tube in priming relation with the cap, and without dislodging the cap.

10 It is a still further object of the invention to provide a tubular member having a blasting cap securely attached thereto such that an inserted explosive cartridge will be firmly and securely held in priming relation with the detonating end of the blasting cap.

15 A further object of the invention is the provision of a primer tube in which the attached blasting cap is covered partially or completely by a ramp member thus facilitating insertion of a 20 dynamite cartridge.

25 A still further object of the invention is the provision of a primer tube having an electric blasting cap securely attached thereto and which serves, when an explosive cartridge is not inserted, as a container for the leg wires of the 30 electric blasting cap.

Another object of the invention is the provision of a primer tube which overcomes the disadvantages of prior known methods of priming explosive charges.

Other objects will appear hereinafter.

The objects of my invention are, in general, accomplished by providing a tubular member, herein designated a primer tube, which is of such 35 diameter and length that an explosive cartridge may be easily but snugly inserted therein. The tubular member may desirably consist of an outer, comparatively rigid, member and an inner member which snugly fits inside the outer member. A blasting cap is threaded through slits 40 in the tubular member and has its inner portion securely held in place between the inner and outer members. The inner end of the cap is entirely covered by the inner member, thus 45 forming a ramp which allows the dynamite cartridge, even though quite hard, to slip over the end of the cap. The inserted cartridge is in close priming relation with the blasting cap and may be readily detonated thereby.

50 Having now indicated in a general way the nature and purpose of the present invention, there follows a more detailed description of a preferred embodiment thereof, with reference to the accompanying drawing, wherein Figure 1 is a 55 longitudinal view of the device; Figure 2 is a cross-sectional view on line 2—2 of Figure 3; Figure 3 is a longitudinal cross sectional view taken on line 3—3 in Figure 1; Figure 4 is a longitudinal view showing the primer tube with an inserted explosive cartridge and Figure 5 is a

cross-sectional view taken on line 5—5 of Figure 4.

Referring more specifically to the drawing herein the numeral 1 designates a primer tube, according to the present invention, which comprises an outer tubular member 2 and an inner tubular member 3, the inner tubular member being so constructed and shaped as to fit snugly within the outer member 2 and to provide a tubular recess 4 into which an electric blasting cap 5 may be inserted. These tubular members may be made of paper, cardboard, plastic, fiber or any other material suitable for the purpose. I prefer to make each of these members of double layer construction, the outer member 2 of two layers of cardboard glued together and the inner layer 3 of two layers of heavy paper glued together.

In joining the blasting cap to the tubular members in accordance with the present invention a transverse slit 6 is made through all four layers of material as shown more particularly in Figures 1 and 3. A second transverse slit 7 is then made in the two outer layers of cardboard only. The section of the tube between the two slits is then pushed inwardly to form a loop 8 (Fig. 2) and the blasting cap inserted through the loop and inwardly between the outer tubular member 2 and the inner tubular member 3. The resulting construction is clearly shown in Figures 2 and 3. It will be noted that the outer portion of the blasting cap rests at its upper portion against the under side of the inner and outer tubes; the intermediate portion of the cap rests at its lower portion in the loop 8 which is formed by the inner tubular member 3 and the portion of the outer tubular member 2 between the slits 6 and 7; the inner portion of the cap rests in the recess 4 formed by the inner tubular member 3 and the outer tubular member 2. This construction forms a very snug pocket for the blasting cap permitting it to be held firmly in place and preventing accidental displacement by the insertion of the dynamite cartridge. If desired, a material such as, for example, glue, rosin, plastic or molten sulfur may be poured into the tubular recess and allowed to harden in order to more positively position the blasting cap.

One of the important features of the improved primer tube according to the present invention is the provision of a ramp 12 over the blasting cap, particularly over the inner portion thereof. In the construction shown, the ramp 12 is formed by a depressed portion of the inner tubular member 3 and extends from a position under the loop 8 back to a position somewhat beyond the end of the blasting cap. It will be noted that the ramp has a gradual slope from its maximum obstructing position to and into the periphery of the inner tube 3. The ramp 12 is supported for the greater part of its length by the enclosed portion of the blasting cap against which it bears. There is, however, a portion 13 from the end of the blasting cap to the point where the ramp merges with the periphery of the tubular member 3, which is shown unsupported. In a great many cases the construction shown is entirely adequate due to the inherent stiffness of the material of which the inner tubular member is made. In other cases it may be necessary or desirable to provide additional supporting means for the portion 13. This may be accomplished in any suitable manner as by the insertion of a solid material having the shape of the open space defined between the portion 13 and the outer

5 tubular member 2. Alternatively, this open space may be filled with a material such as, for example, glue, rosin, plastic or molten sulfur. Upon hardening, this material will adequately support the portion 13 of the ramp 12 and will, in addition, aid in positively positioning the blasting cap.

10 The ramp 12 allows a dynamite cartridge, even though quite hard, to slip easily over the end of the cap. At the same time the split tube construction, together with the paper covering, serves to keep the cap from becoming dislodged. With the primer tube mentioned heretofore, when the end of the blasting cap is left exposed it is sometimes necessary, particularly in the case of hard dynamite, to have a groove pressed in the dynamite to permit easy insertion and lessen the likelihood of the blasting cap being loosened when the cartridge is inserted.

15 Another feature of the invention is that the primer tube, when not in use to prime a dynamite cartridge as, for example, during shipping thereof, may serve as a container in which the leg wires 9 and 10 of the attached electric blasting cap may be securely and expeditiously packed. For this purpose, the leg wires of the cap are folded in the conventional accordion fold and the bundle inserted in the primer tube 1. The leg wires 9 and 10 may, if desired, be tagged to indicate the delay period of the delay electric blasting cap used in the device or the delay period may be printed on the outside of the primer tube itself.

20 Figures 4 and 5 indicate how the primer tube 1 of this invention is to be combined with a dynamite cartridge 11 to quickly effect the construction of a primer ready for use in any explosive operation. Thus the leg wires are removed from the primer tube and the dynamite cartridge 11 inserted as shown. The size of the tube 1 and of the dynamite cartridge 11 are coordinated so that the cartridge is easily slipped into the tube but in such a manner that a snug fit is maintained and close contact is produced between the dynamite cartridge and the detonating end of the blasting cap.

25 It will be realized that various modifications of the device may be resorted to without departing from the spirit and scope of the invention. Thus, for example, in some cases it may be desirable to use a paper sticker in addition to or in place of the inner tubular member. Such a sticker may be made to cover the detonating end of the blasting cap and thus hold it securely in position while at the same time forming a ramp which would facilitate insertion of the dynamite cartridge. This type of construction is very simple and can be used either with or without the loop means 8. If desired, the primer tube of the present invention may be provided with an enveloping label of paper or other suitable material. Such a label may cover the entire tube or a portion thereof, preferably the portion containing the blasting cap. Also, if desired, the inner tubular member may be glued or otherwise fastened to the outer tubular member. In some cases the primer tube may be split longitudinally to permit its use with various sizes of cartridges. In such an event the tube should inherently have or be provided with means to produce sufficient resiliency to securely grip the cartridge. In some cases it may be desirable to provide a plurality of loops 8 rather than the one shown although I have found that the one loop gives very satisfactory results.

Although I have used electric blasting caps as illustrative it is to be understood that other types of commercial electric firing devices such as delay electric blasting caps, fuse blasting caps, etc., may sometimes be used.

It is desirable after the assembly of the complete primer tube to dip the tubes into molten paraffin, rosin-paraffin and/or mixtures of similar materials. This aids in holding the entire assembly together and in water proofing the device.

The primer tube of this invention is particularly useful where it is necessary to prepare primers quickly and under adverse conditions such as, for example, at a tunnel face. It consumes less time and is less dangerous than the old method of making a hole in the dynamite cartridge, inserting a blasting cap therein, and taking the necessary precaution to prevent the cap from being pulled out of the cartridge during the bore hold loading operations. It is much simpler and easier than prior methods thus requiring less skill and labor on the part of the operator. It has the further advantage that a dynamite cartridge may be quickly and easily inserted without loosening or dislodging the firing device.

As various changes may be made in the form, construction and arrangement of parts without departing from the spirit and scope of the invention, it is to be understood that all matter herein is to be interpreted as illustrative and not in a limiting sense.

What I claim and desire to protect by Letters Patent is:

1. An explosive primer adapted to receive and prime a completed explosive cartridge comprising a shock-resistant substantially tubular member, a firing device, resilient means associated with the tubular member for mounting the firing device adjacent the peripheral portion of the tubular member in a snug non-slipping relationship, a lining member within said tubular member which is at least partially cylindrical and which forms a ramp over the said detonating end of the firing device whereby an inserted explosive cartridge slips easily over the said detonating end of the firing device and is held in priming contact therewith.

2. A priming device adapted to receive and prime an explosive cartridge comprising an elongated shock-resistant substantially tubular member, an electric firing device provided with lead wires and having a detonating end, resilient means associated with the tubular member for mounting the firing device adjacent the circumferential portion of said tubular member in a snug non-slipping relationship, said mounting means being constructed and arranged to hold the firing device in a position such that the detonating end thereof is disposed within the interior of the tubular member, a lining member within said tubular member which is at least partially cylindrical and which forms a ramp over the detonating end of said electric firing device whereby upon insertion of an explosive cartridge into the primer the detonating end of the firing device will not form an obstruction and whereby said inserted explosive cartridge has priming contact with said detonating end, said primer serving as a packing case for the lead wires prior to the insertion of an explosive cartridge therein.

3. A priming device adapted to receive and

prime an explosive cartridge comprising an outer paper tube, an inner paper tube snugly fitted within the outer paper tube, said inner paper tube being provided with an inwardly extending portion forming a tubular recess, said recess extending longitudinally of the inner tube, a firing device positioned in said recess and securely fastened therein, a ramp formed by said inner tube from the detonating end of said firing device to the inner periphery of said outer tube and said inner tube having a resistance whereby when an explosive cartridge is inserted into the said priming device, the detonating end of the said firing device will be in priming contact with the said cartridge.

4. A priming device adapted to receive and prime an explosive cartridge comprising a shock-resistant tubular member, said member having a series of transverse cuts dividing a longitudinally extending portion of the surface of said member into a plurality of relatively movable sections, an electric firing device threaded through said sections so that one section passes above the firing device and the adjacent section below it, said firing device having a detonating end extending into the tubular member, a lining member within said tubular member which is at least partially cylindrical and which forms a ramp from the end of said device to the inner surface of said tubular member whereby an explosive cartridge is easily inserted into the said priming device and the detonating end of the said firing device will be in priming contact with the said cartridge.

5. A priming device adapted to receive an explosive cartridge to effectively prime the same comprising a preformed substantially tubular shock-resistant member, a firing device, resilient means for rigidly attaching said firing device to and adjacent the wall of said shock-resistant member in a snug non-slipping relationship, said firing device positioned such that the detonating end thereof is disposed within the tubular member, a lining member within said tubular member which is at least partially cylindrical and which forms a ramp extending from the detonating end of said firing device to the inner surface of said shock-resistant member whereby an explosive cartridge will be easily inserted and will be in priming contact with the detonating end of the said firing device.

6. A priming device adapted to receive and prime an explosive cartridge comprising a longitudinal split tubular member, a series of transverse peripheral cuts in said member adjacent one end thereof, said cuts dividing a longitudinally extending portion of the surface of the tubular member into a plurality of relatively movable strips, an electric firing device threaded through said strips in a manner such that one series of alternate strips pass under the firing device and another series of alternate strips pass over the firing device, said firing device having a detonating end projecting into the tubular member, a lining member within said tubular member which is at least partially cylindrical and which forms a ramp extending from said detonating end of said firing device to the inner surface of said tubular member and a label wrapped around said tubular member and firing device and aiding in holding them in assembled position.
